Guy Borth Janney & Company

UNITED STATES PATENT OFFICE.

GUY MANLY RUSSELL, OF SYRACUSE, NEW YORK, ASSIGNOR TO AMERICAN PIANO COMPANY, OF NEW YORK, N. Y., A CORPORATION OF NEW JERSEY.

POWER-UNIT MOUNTING FOR MUSICAL INSTRUMENTS.

Specification of Letters Patent. Patented June 14, 1921.

1,381,666.

Application filed December 26, 1917. Serial No. 208,759.

To all whom it may concern:

Be it known that I, GUY MANLY RUSSELL, a citizen of the United States of America, residing in the city of Syracuse, in the county of Onondaga and State of New York, have invented an Improvement in Power-Unit Mountings for Musical Instruments, of which the following is a specification.

10 This invention relates to the mounting of a power plant in automatic musical instruments and is particularly adapted for use in grand pianos.

15 The principal object of the invention is to provide an arrangement of parts by which a power plant, herein shown as comprising an electric motor, and a pneumatic exhaust pump may be mounted in an inconspicuous position and so mounted that the vibrations 20 set up during the operation of the power plant will not be transmitted to the frame of the piano in such a way as to set up audible vibrations therein. Other objects 25 of the invention will be apparent from the following description.

In the accompanying drawings, an illustrative embodiment of the invention is shown, and therein—

30 Figure 1 is a plan view of the underside of a grand piano showing the power plant mounted thereon;

Fig. 2 is a section on the line 2—2 of Fig. 1;

Fig. 3 is a section on the line 3—3 of Fig. 1; and

Fig. 4 is a section on the line 4—4 of Fig. 1.

Referring to Fig. 1 of the drawings, the rear part of a grand piano is shown, with its rim or frame 11 and post 12. The power plant is mounted between the frame 11 and the post 12, and consists of a pneumatic exhaust pump 13 driven by a motor 14 through a belt 15.

45 In automatic player pianos or other instruments of this character, it is extremely desirable that no vibrations incident to the operation of the power plant be transmitted to the sounding board of the piano, as such

50 vibrations tend to destroy the effective reproduction of the music. This invention provides vibration absorbing means to support the pump 13, and the motor 14 so that audible vibrations may not be set up in the

piano as the result of operation of its power plant.

Herein the pump 13 is mounted between the post 12 and a part of the frame 11, as shown in Fig. 1. The pump frame is provided with supporting members 16 affixed to the pump casing. These supports enter receptacles 17, which are mounted on the frame of the player instrument. The holes in the receptacles are of greater size than the supports 16, and these supports are surrounded by a vibration absorbing material 18, which is preferably made of a suitable felt. In Fig. 3 it is shown that the supports are entirely surrounded by the felt. The receptacle 17 incloses the felt 18 and the supports with slight pressure so that sliding of the supporting members in the felt is permitted. By insulating the supporting members with felt, the vibrations due to the operation of the pump are largely absorbed and therefore not transmitted to the piano.

Under normal conditions the frame of the pump, as represented by 13, tends to move against the supporting post 12 by reason of the belt or equivalent connection with the motor, and in order to prevent the pump frame from moving into contact with the supporting post 12, vibration absorbing member or felt stop 24 is placed between the pump frame 13 and post 12 as shown in Fig. 1. By such a means of insulation substantially all vibrations of the pump 13 when, under operating conditions, are prohibited from being transmitted to the frame of the player instrument.

90 The motor 14 is provided with a bracket 19 and supported on rods 20 which in turn are supported by the members 21 attached to the frame 11 and post 12. The supporting rods 20 are run through felt bushings 22 in the ends of the bracket 19. The ends of the rods 20 are surrounded by felt pieces 23, as shown in section in Fig. 4, and thereby the vibrations incident to the operation of the motor are prevented from being transmitted to the sounding board of the piano in such a way as to set up audible vibrations therein.

100 Means may be provided to adjust the position of the motor relatively to the pump 105 for the purpose of tightening the driving belt the same being herein shown as a wedge 25 having a vibration absorbing means 26

mounted on its inclined face. The wedge is slidably mounted on the supporting post 12. The wedge may be held in any position by suitable binding apparatus; preferably a plate 27 mounted on the post 12, and having a slot 28 therein which allows a stud 29 to move in the slot and to be tightened when the wedge is in proper position, the stud being adapted to screw into the wedge.

It is to be understood that the present invention may be variously modified and embodied within the scope of the subjoined claims.

15. I claim as my invention:

1. Supporting means for an electric motor comprising, in combination, a yoke affixed to the motor casing, said yoke being provided with bosses bored at right angles 20 to the armature shaft of the motor; a pair of rods passing through said bosses; vibration absorbing bushings for said bosses; supports for the ends of said rods; and vibration absorbing bushings between said 25 rods and said supports:

2. Supporting means for an electric motor comprising, in combination, a yoke affixed to the motor casing, said yoke being

provided with bosses bored at right angles to the armature shaft of the motor; a pair 30 of rods passing through said bosses; supports for the ends of said rods; and vibration absorbing bushings between said rods and said supports.

3. In a power unit for an automatic instrument, a pump associated with the frame of the instrument; supporting extensions from said pump adapted to be slidably received by said frame; vibration absorbing material interposed between said extensions 40 and said frame; an electric motor; means for slidably supporting said motor upon said frame; vibration absorbing material interposed between the motor supports and the frame; and means including vibration 45 absorbing means for spacing said pump and motor upon opposite sides of a central frame member.

In testimony whereof I have signed my name to this specification this 20th day of 50 December, 1917.

GUY MANLY RUSSELL.
